VENDING MACHINE FOR PACKAGED BEVERAGES OR THE LIKE

Channing W. Gilson and Robert D. Mason, Los Angeles, Calif., assignors to Almon C. Woodruff, Van Nuys, Calif.

Application November 7, 1955, Serial No. 38,767

Term of patent 14 years

(Cl. D52—3)

Fig. 1

The display items shown in broken lines in Figure 3 of the drawing are for illustrative purposes only.

We claim:

The ornamental design for a vending machine for packaged beverages or the like, substantially as shown and described.
